LEWIS SMITH AND SAMUEL FOSTER, JR., OF DES MOINES, IOWA.

Letters Patent No. 84,443, dated November 24, 1868.

IMPROVED CURTAIN-FIXTURE.

The Schedule referred to in these Letters Patent and making part of the same.

To all whom it may concern:

Be it known that we, LEWIS SMITH and SAMUEL FOSTER, Jr., of Des Moines, in the county of Polk, and in the State of Iowa, have invented certain new and useful Improvements in Curtain-Fixtures; and do hereby declare that the following is a full, clear, and exact description thereof, reference being had to the accompanying drawings, and to the letters of reference marked thereon.

The nature of our invention consists in the construction of a device for hoisting and lowering window-curtains, which will be hereinafter more fully set forth.

In order to enable others skilled in the art to which our invention appertains, to make and use the same, we will now proceed to describe its construction and operation, referring to the annexed drawings, which form a part of this specification, and in which—

Figure 1 is a front view, and

Figure 2, a side elevation.

A represents a window-casing, and

B, the window.

C is a curtain, which is rolled up on a roller, D, the journals *a a* of which have their bearings in suitable brackets, E E.

At one end of the roller D is a reel, F, on which the cord *e* is rolled.

The journal *a*, on the outside of the reel F, is round, and provided with an indentation, *i*.

A spring, I, is now secured to the window-casing, and so bent as to catch in the indentation *i*, thus holding the roller D still, and preventing the same from turning.

The other end of the cord *e* is secured to the spring I.

It will be seen that it is only necessary to release the spring I from the cog or notch *i*, and the curtain will at once drop down, winding the cord *e* up on the reel F, and when it is desired to hoist the curtain, pull on the cord thus wound up, when the roller D will turn, winding up the curtain. The curtain can, by this arrangement, be placed at any height desired.

Having thus fully described our invention,

What we claim as new, and desire to secure by Letters Patent, is—

In combination with the roller D and its reel F, the elongated journal *a*, provided with an indentation, *i*, within which the bend in the curved spring-rod I is rested, all as herein shown and described.

In testimony that we claim the foregoing, we have hereunto set our hands, this 5th day of October, 1868.

LEW. SMITH.
SAMUEL FOSTER, JR.
